UNITED STATES PATENT OFFICE.

DAVID C. KLAUSMEYER, OF CINCINNATI, OHIO, ASSIGNOR TO THE CINCINNATI BICK-FORD TOOL COMPANY, OF CINCINNATI, OHIO, A CORPORATION OF OHIO.

COLUMN-BINDER-CONTROL LINKAGE.

Application filed August 24, 1921. Serial No. 494,830.

To all whom it may concern:

Be it known that I, DAVID C. KLAUSMEYER, a citizen of the United States, and residing at Cincinnati, in the county of Hamilton and 5 State of Ohio, have invented a new and Improved Column-Binder-Control Linkage, of which the following specification is a full disclosure.

This invention relates to radial-drills and 10 it deals more especially with improvements in the means for restraining the radial-arm against swinging in a horizontal plane about the post or column from which it adjustably extends.

15 In radial-drills, the drill-head is carried by a horizontal arm which is pivotally supported at one end only by means of an appropriate post or column. The pivot may be of various types and in one of its best 20 forms consists of an elongated tubular sleeve which is rotatably supported by a rigid post. The radial-arm is arranged to be raised and lowered on the sleeve and is usually splined thereto and capable of being clamped rigidly to the sleeve for the purpose of maintaining its elevation. When the user desires 25 to adjust the lateral position of the drill-point, he swings the arm and the sleeve as a unit about the post and, when ready to proceed 30 with the drilling operation, he causes the sleeve to be clamped to the post so as to prohibit any swing of the arm. Machines of this nature are usually quite large and the 35 various major frame-elements are quite ponderous and, as a consequence, there is considerable frictional resistance to the movements aforesaid. Therefore, the workman will habitually turn the arm by pressing against its outermost extremity so as to obtain 40 the benefit of as much leverage as possible. In previous constructions, it has been necessary for the machinist to leave his point of vantage and go to the column for the purpose 45 of clamping the sleeve rigidly on the post. This not only occasioned a loss of time but also interfered somewhat with obtaining a nicety in the adjustment of the drill-point to the casting.

This invention aims to overcome this in- 50 conveniences inherent in conventional machines by providing a mechanical connection between the clamp located at the base of the sleeve and a hand-lever located immediately adjacent the outermost extremity of the arm 55 where the user can operate it to the greatest

advantage. The invention also has in objective a mechanical connection of the sort described which will admit of vertical adjustments of the arm on the sleeve without any interference. It also seeks to provide a mechanical connection which will be simple in construction, neat in appearance and so located as to be in general out of the way of the user.

Other objects and advantages will be in part 60 indicated in the following description and in part rendered apparent therefrom in connection with the annexed drawings.

To enable others skilled in the art so fully 65 to apprehend the underlying features hereof that they may embody the same in the various ways contemplated by this invention, drawings depicting a preferred typical construction have been annexed as a part of 70 this disclosure and, in such drawings, like 75 characters of reference denote corresponding parts throughout all the views, of which:—

Fig. 1 is an elevation, partly in section, of the rear-side of a radial-drill equipped with 80 this invention. Fig. 2 is a fragmentary rear end-view showing the connection extending from the hand-operated rod to the clamp itself and showing the provision whereby 85 the arm may be raised and lowered on the sleeve without interference. Fig. 3 is a horizontal section through the plane indicated by the trace 3—3.

Referring to the drawings, A indicates the 90 base of a radial-drill and B indicates a post or column secured to the rear end of the base, as by means of bolts 1 and 2. This post is in the form of a hollow tubular casting suitably fashioned and constructed interiorly for the purpose of receiving a power-transmitting shaft 3 which, by means 95 of gears 4 and 5, derives motion from a power-shaft 6.

Circumscribing the post B is a tubular sleeve C which is suspended at its upper end by suitable ball and thrust-bearings 100 which, being entirely conventional, are not shown but which may be arranged as set forth in my United States Patent No. 1,374,581. The lower part of this sleeve C enlarges to form the bell 7 which is circumferentially cut as indicated by 8 and also transversely thereto as indicated by 9 to provide slightly flexible wings 10 and 11. These wings are provided with lugs 12 and 13 which, by means of a draw-bolt 14 (actu- 110

ated by an eccentric 15 on the shaft 16 journaled in the parts 17 and 18) may be drawn together to clamp the sleeve on the brake surface 19 of the post. That is to say, by rotating the shaft 16 through a partial revolution, the sleeve may be clamped or unclamped at will. In previous machines, the manually-operated clamp-lever has habitually been secured directly to the shaft 16, or its equivalent, and hence has been located most inaccessibly to the person who is adjusting the horizontal position of the arm.

This invention proposes a mechanical connection leading from the shaft 16 to the outermost extremity of the arm, or to some other convenient point thereon, and this connection comprises a shaft which may either be an extension of the upright shaft 16 or a separate shaft 20 connected to shaft 16 by a coupling 21 sufficiently flexible to compensate for the slight relative movements of the parts. The shaft 20 extends vertically alongside of the rear end of the tubular sleeve-like portion D' of the radial-arm D and this portion D' carries a housing 22 for a gear-segment 23 which is splined, as by means of a feather 24, to the shaft 20 so that, as the arm D is raised or lowered, the gear-segment 23 will be carried with it while preserving its power-transmitting relation with the shaft 20. The housing 22 also provides a slideway 25 within which may reciprocate a slide-bar 26; said bar being retained in place by a cover-plate 27. This slide-bar is provided adjacent one end of its forward vertical edge with rack-teeth 28 which are in mesh with the teeth of the gear-segment 23. This slide-bar 26 is translated by means of a gear-segment 29 meshing with rack-teeth 30 in the under edge of the slide-bar, as shown best by Fig. 2. The gear segment 29 is secured to the end of an elongated shaft 31 which is preferably journaled at its forward end in a bracket 32 located at the outermost extremity of the arm D and it is likewise journaled in a block or support 33 affixed to the rear sleeve-like end of the arm D. To keep this shaft clear of the working elements on the front of the arm, this shaft is preferably arranged alongside the rear side of the arm where it is out of the way.

To enable the shaft 31 to be manually rotated from a point immediately adjacent the outermost extremity of the arm D, a hand-grasp 34 in the nature of a lever is arranged on the outer end of the shaft 31. To enable this hand-grasp to be given whatever angular position will correspond most convenient to the initial point of rotation for clamping purposes, its hub 35 is preferably loose and shiftable on the shaft but is provided with teeth 36 adapted to be meshed with corresponding teeth on a clutch collar

37 affixed to the shaft 31. By this means, the hand-lever may from time to time be affixed to the shaft 31 in such a way that it may most effectively be manipulated; thus making it easy to take care of the slack and wear in the clamp and the intervening connections. If desired, a hand-lever may be arranged on intermediate portions of the shaft 31 or may be splined to the shaft 20 and mounted on the sleeve-like portion D' of the arm D.

The raising and lowering of the arm D is accomplished as by means of the screw E driven by suitable gears F.

It will be seen from the foregoing that this improvement is well adapted to achieve the objects of the invention in a simple and inexpensive manner so that the user will not be obliged to depart from his regular station of observation for the purpose of clamping the arm against movement in a horizontal plane.

Without further analysis, the foregoing will so fully reveal the gist of this invention that others can, by applying current knowledge, readily adapt it for various utilizations by retaining one or more of the essential characteristics of either the generic or specific aspects of this invention, and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

1. A radial-drill comprising an upright post; a sleeve rotatably mounted on said post; a radial arm slidably mounted on said sleeve; a clamp located at the base of said sleeve for binding the sleeve to said post and having a slot therein on the side of the post opposite to the arm; a horizontal shaft located back of said arm; a vertical shaft located on said sleeve on the side opposite to said arm for operating said clamp; mechanism for operatively connecting the horizontal shaft to the vertical shaft while permitting vertical movement of the horizontal shaft and arm with respect to the vertical shaft; an operating handle located on the horizontal shaft at the outer end of the arm for solely operating the shafts and said clamp; and clutch means for connecting the operating handle to the horizontal shaft and for permitting the adjustment of the handle with respect to the horizontal shaft.

2. A radial-drill comprising an upright post; a sleeve rotatably mounted on said post; a radial arm slidably mounted on said sleeve; a clamp located at the base of said sleeve for binding the sleeve to said post and having a slot therein on the side of the post

20

25

30

opposite to the arm; a vertical shaft located on said sleeve on the side opposite to the arm for operating said clamp; a horizontal shaft located back of the said arm; a rack and gear mechanism for operating the vertical shaft by the horizontal shaft while permitting vertical movement thereof with respect to the vertical shaft; and an operating handle adjustably located on the horizontal shaft at the outer end of said arm.

3. A radial-drill combining an upright post; a sleeve rotatable thereon; an arm radiating from said sleeve and having a tubular portion vertically shiftable thereon; a clamp located at the base of said sleeve for binding the sleeve to said post; a vertical shaft operatively connected at one end with said clamp, said shaft being located at

one side of a vertical plane intersecting the arm and the axis of said sleeve; a horizontally disposed shaft journaled lengthwise of said arm at the opposite side of said plane and back of the arm; an operating handle adjustably secured to one end of said horizontal shaft at the end of the arm; a gear segment fixed upon the opposite end of said horizontal shaft; a gear segment splined to said vertical shaft; a housing secured to the tubular portion of said arm; and a horizontally disposed rack-bar slidably mounted in said housing and extending across said plane and operatively connecting said gear segments.

In witness whereof, I hereunto subscribe my name.

DAVID C. KLAUSMEYER.
